(57) **CLAIM**

The ornamental design for a biosensor, as shown and described.

DESCRIPTION

FIG. 1 is a front perspective view of a biosensor showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view showing the biosensor in a state of use connected to a broken line sample-collection element via a cable. The broken lines are for the purposes of showing environmental structure in the form of the sample-collection element and the cable, and the broken lines form no part of the claimed design.

The biosensor may be used to detect biomolecules. For example, the biosensor may be used to detect COVID-19 neutralizing antibodies. A sample may be placed on the sample-collection element, and the details of the sample are sent to the biosensor via the cable, so that the sample may be analyzed further.

1 Claim, 8 Drawing Sheets
